PATENTED DEC. 22, 1903.

A. C. MURPHY.

PNEUMATIC HAMMER.

APPLICATION FILED MAY 17, 1901.

NO MODEL.

UNITED STATES PATENT OFFICE.

ALBERT C. MURPHY, OF EAST ST. LOUIS, ILLINOIS, ASSIGNOR TO STANDARD RAILWAY EQUIPMENT COMPANY, A CORPORATION OF ILLINOIS.

PNEUMATIC HAMMER.

SPECIFICATION forming part of Letters Patent No. 747,751, dated December 22, 1903.

Application filed May 17, 1901. Serial No. 60,693. (No model.)

To all whom it may concern:

Be it known that I, ALBERT C. MURPHY, a citizen of the United States, and a resident of the city of East St. Louis, county of St. Clair, 5 and State of Illinois, have invented certain new and useful Improvements in Pneumatic Hammers, of which the following is a specification.

My invention relates to pneumatic hammers, and has for its principal objects to increase the force of the blow and to minimize shock and vibration. It consists in the construction and arrangements of parts herein-after described and claimed.

15 In the accompanying drawings, which form part of this specification, and wherein like symbols refer to like parts wherever they occur, Figure 1 is a longitudinal sectional view of my hammer with the piston in its rearward position. Fig. 2 is a longitudinal sectional view thereof with the piston in its forward position. Fig. 3 is a detail view of the piston. Fig. 4 is a longitudinal sectional view of the valve-block. Fig. 5 is a view of the 25 rear end of the valve-block. Fig. 6 is a view of the front end of the valve-block. Figs. 7, 8, and 9 are cross-sectional views of the valve-block on the lines 7 7, 8 8, and 9 9, respectively, of Fig. 4. Fig. 10 is a cross section 30 of the end plate; and Figs. 11 and 12 are views of the rear and front sides thereof, respectively. Fig. 13 is a detail of the valve.

The principal elements of the present construction are a cylinder 1, a piston 2 therein, 35 a valve-block 3, and a valve 4 therein, and a handle 5, all assembled in the general manner common in tools of this kind. The front end of the cylinder is open, and its nose is adapted for the reception of the shank of a 40 chisel or other tool 6. The rear end of the cylinder is closed by a plate 7, interposed between the cylinder and the valve-block. The valve-block is a cylindrical piece having a cylindrical bore arranged axially, the front 45 end of said bore being of larger diameter than the rear portion thereof. The valve is a cylindrical plug whose front portion is of larger diameter than the rear portion, the two portions being made to fit and slide in 50 the corresponding portions of the valve-block. The handle portion comprises a grasping-

handle 8 and an internally-screw-threaded socket-piece 9. The valve-block fits in this socket-piece and is clamped firmly in position by means of a threaded collar 10, which works in the thread of the socket-piece and has a circumferential shoulder 11 arranged to bear against a shoulder 12 at the end of the cylinder.

The main supply-duct 13 extends from the 60 end of the grasping portion of the handle through said handle into the socket portion, and thence into a chamber 14, formed in the rear end of the valve-block, whereby the rear end of the valve is exposed at all times to the 65 pressure from the source of supply.

From the chamber 14 in the rear of the valve-block a passage-way 15 extends forward through said valve-block to a point close to the front end thereof, and thence inwardly, 70 and opens through a small port 16 into the bore of said valve-block in position to be covered by the valve in its forward position, but to be uncovered when the valve is in its rearward position. Another small port 17, which 75 opens into the bore of the valve-block in the same annular plane as the port 16, connects with a passage way 18, extending from the front end of the valve-block and opening through a port 19 into the smaller bore of the 80 valve-block, said port 19 being in position to be covered by the smaller diameter of the valve when the valve is in its rearward position and to be in register with a groove 20 in 85 said valve when the valve is in its forward position. Back of said last-mentioned port 19 is a port 21, which opens into the smaller bore of the valve-block and communicates with a passage-way 22, extending radially 90 through the valve-block and communicating with the space surrounding the valve-block, which space is permanently open to the atmosphere through the exhaust-port 23 in the socket-piece of the handle. This last-mentioned port 21 is in position to register with 95 the groove 20 of the valve in all positions of the valve. Back of this last-mentioned port 21 and near the end of the valve-block is an annular groove 24 in the small bore of the valve-block. The annular groove 24 is in position to register with the groove 20 of the valve when the valve is in its rearward posi-

tion and to be uncovered by the end of the valve when the valve is in its forward position. This groove 24 communicates with a passage-way 25, extending forwardly through 5 the valve-block and the end plate and opening into the rear end of the cylinder, whereby when the valve is in its forward position the pressure is supplied directly from the source of pressure and through the chamber 14 in 10 the rear of the valve-block, thence to said annular groove 24, and thence through the passage-way 25 to the rear end of the cylinder.

Extending from the chamber 14 in the rear end of the valve-block is a passage-way 26, 15 which extends forwardly through said valve-block and the plate 7 and the wall of the cylinder and opens into the cylinder through a port 27 at a point directly behind the rear end of the piston when the piston is in its 20 extreme forward position. In the same annular plane with this port 27 is a second port 28, which opens into a passage-way 29 in the wall of the cylinder, which communicates with a port 30 in the front side of the plate 7. 25 This port 30 opens into a passage-way 31, extending radially through said plate to the center thereof and thence opens through a port 32 in the rear side of said plate. The piston is provided with a circumferential 30 groove 33 near its rear end, whereby the ports 27 and 28 are brought into communication with each other when the piston approaches the limit of its forward stroke. When the groove 33 thus registers with the two ports 35 27 28, live air is admitted through the passage-way 26, port 27, groove 33, port 28, passage-ways 29 and 31 into the valve-chamber immediately back of the plate. The area of the front end of the valve being larger than the area of 40 the rear end the valve is forced backwardly, whereby the valve covers the groove 24 in the valve-block, and thereby cuts off the live air from the rear end of the cylinder-chamber. During the forward movement of the piston 45 the front end of the cylinder is exhausted through a port 34 near the forward end of the chamber, which port communicates with a passage-way 18, extending back through the wall of the cylinder and the head-block, and 50 communicating with the passage-way 18, which opens through the port 19 into the valve-chamber opposite the groove 20 in the valve, and thence through the passage-way 22 directly to the atmosphere. When the valve 55 is moved to its rearward position, as hereinbefore described, live air is admitted through the passage-way 15 and its port 16 in front of said valve, and thence through the port 17 into the passage-way 18, which leads to the 60 port 34 at the forward end of the cylinder, the other port 19 of said passage-way 18 being at the same time closed by the valve in its rearward position. The piston is thus forced backwardly by the live air admitted in front of 65 it. At the same time the rear end of the cylinder is exhausted through the passage-way 25, extending through the plate and terminat-

ing in the circumferential groove 24 in the valve-block, which groove in the rearward position of the valve is in register with the 70 groove 20 of the valve, and thereby in communication with the exhaust-port 21, which communicates directly with the atmosphere.

In addition to the regular exhaust passage-way 22 I provide a supplemental exhaust 75 passage 35, having a port 36 opening into the cylinder at a point in position to be covered by the piston when it has traveled about one-third of its stroke. This port communicates with the passage-way 35, which extends 80 through the wall of the cylinder and the plate and the valve-block, and opens into the space surrounding said valve-block at a port 37. The port 37 is permanently in communication with the atmosphere. 85

The front end of the cylinder has a shoulder 38 to prevent the accidental coming out of the piston, and the piston is reduced at its forward end, so as to clear the shoulder in delivering its blow to the tool. 90

In case the piston should make an abnormal stroke by reason of the withdrawal of the tool it is held in its forward position by means of pressure admitted in the rear thereof through the port 27, which communicates permanently with the source of pressure through the passage-way 26. The main admission and exhaust port 34 for the front end of the cylinder is covered by the piston in such abnormal position. In order to prevent the 100 movement of the piston from this position, the passage-way 29 is provided with a port 39, opening into the cylinder in the same plane as the port 36 of the exhaust-passage 35. By this arrangement the groove 33 of the piston 105 will register with both the ports 36 and 39 when the piston is abnormally advanced, and therefore the pressure admitted through port 27 into the cylinder-chamber will escape through port 28, passage-way 29, port 39, piston-groove 33, port 36, and passage-way 35 in sufficient quantity to permit the rapid reciprocation of the valve without affecting the movement of the piston. The space back of the shoulder of the valve is open to the atmosphere 115 through a relief-passage 40 specially provided therefor. In order to prevent the violent impact of the valve against the plate 7, which constitutes the front wall of the valve-chamber, it is preferable to form socket-holes 43 in the rear side of said plate. The valve-block is provided with dowel-holes 41 120 44 45 for assembling the parts in proper position.

The operation of this construction is as follows: When the valve and piston are in the positions shown in Fig. 1, the piston is at the limit of its rearward stroke and the valve has shifted so as to admit pressure to the rear end of the piston-chamber. In this condition pressure is admitted through the supply-duct 13, chamber 14 in the rear of the valve-groove 24, and passage-way 25, directly 125 into the rear end of the piston-chamber.

The front end of the piston-chamber is open to the atmosphere through the port 36, passage-way 35, and port 37, and also through the port 34, passage-way 18, port 19, valve-groove 20, port 21, and exhaust-port 22, and consequently the pressure on the rear end of the piston forces said piston forwardly to deliver its blow to the shank of the tool 6 in the fore end of the cylinder. Just before the piston reaches the forward limit of its stroke its groove 33 registers simultaneously with the port 27 of the passage 26, which is permanently connected to the supply-duct and with the port 28, which communicates through the passage-way 29 in the wall of the cylinder with the port 30 of the passage-way 31, arranged transversely in the valve-plate and opening through the port 32 into the valve-chamber in front of the larger end of the valve. In this position of the piston pressure is admitted from the supply-duct through the ports, passage-ways, and groove just mentioned into the front end of the valve-chamber, and said front end being of larger diameter than the rear end such pressure effects the backward movement of the valve into the position shown in Fig. 2. In this position the rear end of the valve cuts off the pressure from the rear end of the piston-chamber and at the same time brings the port 24, which is connected by the passage-way 25 with the rear end of the piston-chamber, into register with the valve-groove 20, which valve-groove also registers with the exhaust-port 21 and passage-way 22 and thence to the atmosphere. In this rearward position of the valve the front end of the valve has uncovered the port 16, which communicates through the passage 15 with the supply-duct, and therefore admits pressure into the front end of the valve-chamber directly from the source of supply. From the front end of the valve-chamber pressure is admitted through the passage-way 17, which has likewise been uncovered by the valve in its rearward movement into the passage-way 18, and thence through the port 34 into the front end of the piston-chamber, the rearmost port 19 of this passage 18 being closed by the valve in its rearward position. In this position, therefore, pressure is admitted to the front end of the cylinder through the front end of the valve-chamber and the ports and passage-ways in communication therewith and is exhausted from the rear end of the piston-chamber through the passage 25 and the groove of the valve and the exhaust-port. Consequently the piston is driven rearwardly. The first effect of the rearward movement of the piston is to carry the piston-groove out of register with the ports 27 and 28. As the piston continues to move rearwardly the front end of the valve-chamber is opened to exhaust by the piston uncovering the port 39 of the passage-way 29, which communicates with the front end of the valve-chamber by means of the passage-way 31 and port 32 of the valve-plate. This brings the front end of the valve-chamber into communication with the front end of the piston-chamber, and the front end of the piston-chamber is at the same time opened to exhaust through the port 36, passage-way 35, and port 37, thereby bringing the front end of the valve-chamber into communication with the atmosphere. The pressure being thus released in the front end of the valve-chamber, the pressure on the rear end of the valve-chamber forces the valve forwardly into the position shown in Fig. 1, the piston meanwhile continuing its rearward movement to the position also shown in Fig. 1. The operation above described is then repeated. In the rearmost position of the piston pressure is admitted to the front end of the piston-chamber through the port 27, but is exhausted therefrom through the ports 34 and 36, so as in no way to interfere with the forward movement of the piston. It is noted that in the normal stroke of the piston the admission and exhaust port 34 near the front end of the piston-chamber is always uncovered. When, however, the piston makes an abnormally-long stroke, as by reason of the shank of the tool being withdrawn, this port 34 is closed by the piston in its abnormal position. In such position the ports 27 and 28 are back of the rear end of the piston, and pressure is admitted through the port 27 into the rear end of the piston-chamber, tending to hold the piston in its abnormal position. This pressure escapes partially through the port 28, passage-way 29, port 39, groove 33, port 36, passage-way 37 to the atmosphere; but part of such pressure passes through the port 28, passage-way 29, and passage 31 to the front end of the valve-chamber in sufficient quantity to effect the backward movement of the valve. The backward movement of the valve has the effect of exhausting the rear end of the piston-chamber, and thereby relieving the pressure in the front end of the valve-chamber also, whereupon the valve is forced forwardly by the constant pressure on its rear end. The port 16, which is uncovered by the valve in its backward movement, being small in comparison with the cylinder-ports, does not admit sufficient pressure to prevent this operation of the valve. The valve thus continues to reciprocate so long as the piston is in its abnormally-forward position.

What I claim as new, and desire to secure by Letters Patent, is—

1. A pneumatic hammer comprising a cylinder having ports for the admission and release of air, a piston in said cylinder and a valve for controlling the admission and release of air, said valve being of the differential-piston type and having its smaller end exposed to constant pressure and having a groove in its smaller diameter arranged to communicate at all times with a main release-port and to communicate alternately with the respective ends of the cylinder, the cylinder

having a supplemental exhaust-port located in the forward portion thereof in position to be uncovered by the piston shortly before the completion of its return stroke, and said 5 piston having also a port communicating with the larger end of the valve-chamber and arranged to be uncovered by the piston simultaneously with the supplemental exhaust-port, substantially as described.

- 10 2. A pneumatic hammer comprising a cylinder having ports for the admission and release of air, a piston in said cylinder and a valve for controlling the admission and release of air, said valve being of the differential-piston type and having its smaller end exposed to constant pressure and having a groove in its smaller diameter arranged to communicate at all times with a main release-port and to communicate alternately 15 with the respective ends of the cylinder, the cylinder having a supplemental exhaust-port permanently open to the atmosphere and located in the forward portion thereof in position to be uncovered by the piston shortly 20 before the completion of its return stroke, and said piston having also a port communicating with the larger end of the valve-chamber and arranged to be uncovered by the piston simultaneously with the supplemental 25 exhaust-port, substantially as described.

3. A pneumatic hammer comprising a handle portion, a cylinder, a piston in said cylinder, a valve-block having ports for the admission and release of air, and a solid plug-valve of the differential-piston type for controlling the admission and release of air, said 35 valve being located in a separate valve-chamber back of said cylinder and in alignment therewith and having a circumferential 40 groove in its smaller portion, all arranged to coöperate, substantially as described.

4. A pneumatic hammer comprising a handle portion, a cylinder, a valve-block having ports for the admission and release of air, 45 and a solid plug-valve of the differential-piston type for controlling the admission and release of air, one of said ports being in front of said valve and communicating through a passage-way with the middle portion of said 50 cylinder, said valve being in a separate valve-chamber located back of said cylinder and having a circumferential groove in its smaller portion to coöperate with the main exhaust-port, and having its larger diameter at the 55 front end, substantially as described.

5. A pneumatic hammer comprising a handle, a cylinder, a piston therein having a groove near its rear end, a valve-block, a valve having a groove near its rear end, and 60 ports and passage-ways for the admission and release of air, the rear end of the valve being of smaller diameter than the front end and exposed to constant pressure, the front end of the valve-chamber being provided with 65 small ports in position to be covered and uncovered by said valve, and communicating respectively with the source of pressure and

with the front end of the piston-chamber, the latter passage-way also opening into the valve-chamber in position to register with the valve-groove when the valve is in its forward position, said hammer also being provided with passage-ways opening into the piston-chamber at a point adapted to register with the groove in the piston when the piston is in its 75 normal forward position, one of said passage-ways being connected to the source of pressure, and the other of said passage-ways being connected to the front end of the valve-chamber, and said hammer having a passage-way extending from the rear end of the piston-chamber into the valve-chamber at a point adapted to be traversed by the rear rib of the valve, and an exhaust-port in register at all times with the groove in said valve, 85 substantially as described.

6. A pneumatic hammer comprising a handle, a cylinder, a piston therein having a groove near its rear end, a valve-block, a valve having a groove near its rear end, and 90 ports and passage-ways for the admission and release of air, the rear end of the valve being of smaller diameter than the front end and exposed to constant pressure, the front end of the valve-chamber being provided 95 with small ports in the same annular plane in position to be covered and uncovered by said valve, and communicating respectively with the source of pressure and with the front end of the piston-chamber, the latter 100 passage-way also opening into the valve-chamber in position to register with the valve-groove when the valve is in its forward position, said hammer also being provided with passage-ways opening into the piston-chamber 105 at a point adapted to register with the groove in the piston when the piston is in its normal forward position, one of said passage-ways being connected to the source of pressure, and the other of said passage-ways being 110 connected to the front end of the valve-chamber, and said hammer having a passage-way extending from the rear end of the piston-chamber into the valve-chamber at a point adapted to be traversed by the rear rib 115 of the valve, and an exhaust-port in register at all times with the groove in said valve, substantially as described.

7. A pneumatic hammer comprising a cylinder, a piston therein, a handle having a socket 120 therein, and a hollow cylindrical valve-block in said socket arranged to form a chamber at the rear of said valve-block in communication with the source of pressure and with the rear end of the bore of the valve-block, a differential valve in the bore of the valve-block having its large area in the front end of the valve-block, a plate between the cylinder and valve-block constituting the front wall of the valve-chamber, said plate having a port opening into said valve-chamber and communicating with the source of pressure through 125 passage-ways and ports controlled by the piston, substantially as described.

8. A pneumatic hammer comprising a cylinder, a piston therein, a handle having a socket therein, and a hollow cylindrical valve-block in said socket arranged to form a chamber at the rear of said valve-block in communication with the source of pressure and with the rear end of the bore of the valve-block, a differential valve in the bore of the valve-block having its large area in the front end of the valve-block, a plate between the cylinder and valve-block constituting the front wall of the valve-chamber, said plate having a port opening into said valve-chamber and communicating with a port in the wall of the cylinder in position to register with a groove in the rear portion of the piston when the piston is in its forward position, said hammer also having a passage-way communicating with the source of pressure and having a port in the wall of the cylinder arranged to register with said piston-groove simultaneously with said last-mentioned port, substantially as described. 50
9. A pneumatic hammer comprising a cylinder, a piston therein, a handle having a socket therein, and a hollow cylindrical valve-block in said socket arranged to form a chamber at the rear of said valve-block in communication with the source of pressure and with the rear end of the bore of the valve-block, a differential valve in the bore of the valve-block having its large area in the front end of the valve-block, a plate between the cylinder and valve-block constituting the front wall of the valve-chamber, said plate having a port opening into said valve-chamber and communicating with the source of pressure by ports and passage-ways arranged to be controlled by the piston, the front end of the valve-chamber communicating with a port which opens into the cylinder in position to be uncovered by the piston near the completion of its return stroke, said hammer having a supplemental exhaust-port opening into said cylinder opposite said last-mentioned port, and being permanently open to the atmosphere, substantially as described. 55
10. A pneumatic hammer comprising a cylinder, a handle having a socket therein, and a hollow cylindrical valve-block in said socket, a valve in the bore of the valve-block, and a plate between the cylinder and valve-block constituting the front end of the valve-chamber, said plate having small socket-holes therein adapted to cushion the valve, substantially as described. 60
11. A pneumatic hammer comprising a cylinder, a piston therein, a handle having a socket therein, and a hollow cylindrical valve-block in said socket arranged to form a chamber at the rear of said valve-block in communication with the source of pressure and with the rear end of the bore of the valve-block, a differential valve in the bore of the valve-block having its large area in the front end of the valve-block, and a plate between the cylinder and valve-block constituting the front wall of the valve-chamber, said valve having a groove near its rear end, and said block having an exhaust-port always in register with said groove, and a passage-way opening into the valve-block in position to be traversed by the rear end of the valve and communicating directly with the rear end of the piston-chamber, and said valve-block having also a passage-way communicating with the source of pressure and opening through a small port into the valve-chamber in position to be covered and uncovered by the front end of the valve, and said valve-block having a passage-way opening into the front end of the cylinder, and having two openings into the bore of the valve-block, one of said openings being opposite the small opening hereinbefore mentioned, and the other opening being in position to register with the groove in the valve when the valve is in its forward position, substantially as described. 65
